(57) CLAIM

The ornamental design for a box for pasta, as shown and described.

DESCRIPTION

FIG. 1 is a front, right side and top perspective view of a box for pasta showing the new design;

FIG. 2 is a front elevational view thereof;

FIG. 3 is a rear elevational view thereof;

FIG. 4 is a top plan view thereof; and,

FIG. 5 is a bottom plan view thereof.

The appearance of the right and left sides of the box is not claimed.

The broken line showing is included for the purpose of illustrating only and forms no part of the claimed design.
